DECORATIVE TUBE FOR COSMETIC CONTAINERS, PERFUME BOTTLES AND THE LIKE

Philip E. Kettell, North Kingston, R.I., assignor to E. A. Adams & Son Inc., Pawtucket, R.I., a corporation of Rhode Island

Filed Oct. 16, 1963, Ser. No. 77,006

Term of patent 7 years

(Cl. D86—10)

FIG. 1

FIG. 3

FIG. 1 is a perspective view of a decorative tube for cosmetic containers, perfume bottles and the like embodying my new design.

FIG. 2 is an end view thereof.

FIG. 3 is an enlarged fragmentary view of the portion of the tube showing the details of the design.

I claim:

The ornamental design for a decorative tube for cosmetic containers, perfume bottles and the like, as shown.
